UNITED STATES PATENT OFFICE.

WILLIAM M. BRADSHAW, OF WILKINSBURG, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed September 23, 1921. Serial No. 502,677.

My invention relates to relays and particularly to thermal relays of the cartridge type.

One object of my invention is to provide a thermal relay that shall have means for reinforcing the same to effectively maintain the co-operating portions of the relay in alinement.

Another object of my invention is to provide a thermal relay employing a bimetallic element that shall not require auxiliary conductors for connecting the bimetallic elements in series with the ferrules that are disposed at the respective ends of a casing enclosing the bimetallic element.

A further object of my invention is to provide a relay, of the above-indicated character, in which a bimetallic element and a contact member to be engaged thereby shall be disposed at the respective ends of the relay and shall be provided with means for precluding a relative movement between the various elements.

A further object of my invention is to provide a thermal relay, of the above-indicated character, that shall embody means for permitting observation and adjustment of the contact member within the casing and for closing the casing to the surrounding air.

A still further object of my invention is to provide a relay of the above-indicated character that shall be simple and inexpensive to construct, easy to assemble, and effective and reliable in its operation.

In practicing my invention, I provide a tubular conducting member, a cylindrical insulating casing therefor, a bimetallic element and an adjustable contact member that is adapted to be engaged by the bimetallic element. The contact member and the bimetallic element are supported by bushings, of molded insulating material, that are securely disposed at the respective ends of the cylindrical insulating casing. The bimetallic element is slotted from opposite ends to increase the resistance thereof and to provide two terminals therefor at one end.

One terminal of the bimetallic element is adapted to be soldered to the tubular conducting member, and the other terminal of the bimetallic element is adapted to be soldered, or otherwise connected, to one of the end ferrules. The other end ferrule is pro-

vided with internal threads whereby the ferrule may be screwed upon the other end 55 of the tubular conducting member to effect engagement therewith.

The cylindrical casing of insulating material is disposed around the conducting tubular member between the end ferrules. 60 The casing is slotted to permit it to be readily moved with respect to the conducting member to compensate for high spots on the latter. The tubular conducting member is provided with three apertures opposite the 65 contact member that is to be engaged by the bimetallic element, and the insulating casing is also provided with a single aperture through which, when alined with the apertures in the conducting member, the contact 70 member and the bimetallic element may be observed and adjusted, after which the insulating casing may be further turned to close the conducting member to the outer 75 air.

Figure 1 of the accompanying drawings is a perspective view of a thermal relay embodying my invention, and

Fig. 2 is a plan view, partially in section, of the relay shown in Fig. 1, and 80

Fig. 3 is a side elevational view of the insulating casing.

The relay comprises, in general, a tubular conducting member 1, a bimetallic element 2 and a stationary supporting member for 85 an adjustable contact member 3, both of which are disposed within the tubular conducting member, two supporting bushings 4 and 5 for the bimetallic element and the contact member, respectively, a cylindrical 90 casing 6 of insulating material and two end ferrules 7 and 8.

The bimetallic element 2 is slotted from the respective ends thereof to constitute a conductor having a relatively long current-conducting path and a relatively small cross-sectional area. A greater degree of heating is thus obtained and the relay may be caused to operate by currents of relatively small values.

The bimetallic element is rigidly secured, at one end, by being molded as a unit in the bushing 4 of molded insulating material. One terminal 10 of the bimetallic element 2 is adapted to be fitted into a slot 9 in the 105 tubular member 1 and soldered to said mem-

ber whereby rotary movement of the molded bushing 4 is precluded. The other terminal 11 of the bimetallic element is adapted to fit into a slot 12 in the ferrule 7 to be soldered to the same.

The free end of the bimetallic element 2 supports and controls a contact member 13 which is adapted to co-operate with the contact member 3 to control an external auxiliary circuit. The bushing 5 has a small pin 14 disposed in the side thereof that is adapted to fit into a slot 15 in the tubular member 1 to prevent relative movement between the bushing and the tubular conducting member 1. A screw 16 is provided to permit the contact member 3 to be connected to an external circuit that is to be controlled thereby.

The end portion 17 of the conducting member 1 is screw-threaded, and the ferrule 8 is provided with internal threads whereby the ferrule may be securely mounted upon the conducting member 1.

The conducting member 1 is also provided with three apertures 18, 19 and 20 whereby the engagement between the contact member 3 and the contact member 13 may be observed and adjusted.

The insulating casing 6 is provided with a single aperture 21 that may be aligned with those in the conducting tube 1 to permit observation and adjustment of the contact member 3 within the conducting tube. When the aperture 21 is out of registry with the apertures 18, 19 and 20, the tube is closed to the surrounding air to exclude dust and other foreign particles therefrom. The casing 6 also serves thus to retain the heat within the casing 1 and to prevent undue dissipation of the heat therefrom.

The casing 6 is slotted, as illustrated in Fig. 3, at an angle with the axis of the tube to permit two degrees of movement when adjusting the casing to compensate for high spots or irregularities on the external surface of the conducting tubular member 1. The casing 6 fits the tubular member relatively closely and is so held between the ferrules 7 and 8 that it may be turned to align the aperture 21 therein with those in the tubular conducting member 1.

By means of the construction that I employ and have illustrated, it will be seen that the relay embodying my invention is readily and easily assembled. The various co-operating elements are so arranged as to be effectively maintained in alinement. Furthermore, means are provided whereby the relative adjustment of the contact members within the relay may be effected without removing the relay from service or removing it from the ferrules within which it may, at the same time, be disposed.

My invention is not limited to the particular arrangement or structure that is

illustrated, since modifications may be made therein within the spirit and scope of the invention, as set forth in the appended claims.

I claim as my invention:

1. A thermal relay comprising a bimetallic element, a metallic casing therefor, an internally threaded ferrule upon one end of the metallic casing, a ferrule disposed at the other end of the casing and an insulating casing between the latter ferrule and the metallic casing.

2. The combination with a tubular conducting member, of a closely fitting tube of insulating material having two degrees of adjustment to compensate for high spots on the tubular conducting member.

3. A thermal relay comprising a cylindrical conducting member having one end thereof externally threaded, a bimetallic element, a stationary contact member adapted to be engaged thereby, means for securely disposing the bimetallic element and the contact member at the respective ends of the cylindrical member, two end ferrules, one of which is internally threaded to engage the cylindrical conducting member, means whereby the other ferrule may be secured to one end of the bimetallic element, and a cylindrical casing for the cylindrical conducting member, said casing being relatively movable between the ferrules and the conducting member.

4. A thermal relay comprising a cylindrical conducting member having one end thereof externally threaded, a bimetallic element, a stationary contact member adapted to be engaged thereby, means for securely disposing the bimetallic element and the contact member at the respective ends of the cylindrical member, two end ferrules, one of which is internally threaded to be screwed upon the cylindrical conducting member, means whereby the other ferrule may be secured to one end of the bimetallic element, and means co-operating with the conducting member to permit observation and adjustment of the contact member and closing of the conducting member to the surrounding air.

5. A thermal relay comprising a cylindrical conducting member having one end thereof externally threaded, a bimetallic element, a stationary contact member adapted to be engaged thereby, insulating means for supporting the bimetallic element and the contact member at the respective ends of the conducting member and means for precluding relative rotary movement between the conducting member and the supporting means, comprising means for electrically connecting the bimetallic member and the conducting member.

6. A thermal relay comprising a cylindrical conducting member, bushings of electric-

insulating material located in said member, at the respective ends thereof, a stationary contact member supported by the first of said bushings, a longitudinally slotted bimetallic element supported by the second of said bushings and having one of its ends electrically connected to said conducting member, an end ferrule mounted on one end of said conducting member and in electrical connection therewith, a second ferrule mounted on the other end of said conducting member and having the other end of said bimetallic element electrically connected thereto, and an exterior casing of electric insulating material on said conducting member and extending between said ferrules.

7. A thermal relay comprising a cylindrical conducting member having a plurality of spaced apertures therein at one end thereof, two end ferrules, two end bushings, a bimetallic element supported by one of said bushings and having its respective ends electrically connected to one of said ferrules and to said conducting member, a stationary contact member supported by the other of said bushings, and a cylindrical casing for the cylindrical conducting member having a single aperture therein and movable relatively to the ferrules and the conducting member to permit registration of the apertures in the casing and the conducting member for permitting of observation and adjustment of the contact member and closing of the conducting member.

In testimony whereof, I have hereunto subscribed my name this 7th day of September, 1921.

WILLIAM M. BRADSHAW.
